BREECH BLOCK MECHANISM

William Summerbell, Watervliet, N. Y.

Application May 16, 1941, Serial No. 393,762

5 Claims. (Cl. 89—24)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to a breech block operating mechanism for a semi-automatic gun of the type having a vertically sliding breech block.

It is the object of this invention to provide a compact block operating mechanism which is largely on or forward of the breech ring whereby the gun may be mounted and operated in restricted quarters.

It is a further object to simplify assembly and maintenance of the breech mechanism and associated parts.

The specific nature of the invention as well as other objects and advantages thereof will clearly appear from a description of a preferred embodiment as shown in the accompanying drawings in which:

Figure 1 is a left side elevation of the device of this application, partly in section.

Figure 2 is a rear end elevation with the bracket sectioned on the line 2—2 of Fig. 1.

Figure 3 is a left side elevation of a portion of the mechanism sectionalized on the line 3—3 of Fig. 2 with the bracket removed.

Figure 4 is a right side elevation.

Figure 5 is a top plan view.

Figures 6 and 7 are respectively plan and side elevations of the breech operating crank.

Figure 8 is a side elevation of the operating shaft.

Figure 9 is a detailed sectional view of the block operating cam and its supporting bracket taken on the line 9—9 of Fig. 4.

Figure 10 is an enlarged detailed plan view of the drag link retaining pin.

Figure 11 is an enlarged elevation, partly in section of the lever, drag link, and retaining pin.

Referring to the drawings by characters of reference, Figure 1 shows a breech ring 1 in which a breech block 2 is vertically slidable. Depending portions 3 and 4 of the breech ring are bored to provide bearings for the block operating shaft 7 (Fig. 8). The shaft is provided with a laterally extending lever 8 and with bearing surfaces 9 and 10 to be journaled in the breech lugs at 3 and 4. The central portion of the shaft 7 is adapted to receive the crank 11 (Figs. 6 and 7), being provided with keys 12 to engage the key slots 13 in the end of the crank.

The breech block 2 is slidable in a known manner in the breech ring and is formed in its lower

portion with a transverse T-shaped slot 14 extending from the front to the rear faces of the block and having the leg 15 of the T slot intersecting the lower face of the block as best shown in Figs. 2 and 3. The breech block is further provided with rearwardly extending stops 16 for engaging notches 17 in the breech ring to limit the upward movement of the block.

The crank 11 (Figs. 6 and 7) comprises a hollow cylindrical portion 18 adapted to be mounted on the shaft 7 as described above and having a central upwardly extending arm 19 provided at its extremity with block engaging lugs 20 complementary to the T-shaped slot in the block. This arm 19 is further provided with a rearwardly extending handle 21 having a lateral grip portion 22. The crank is further provided with a downwardly extending stop portion 23 adapted to engage a lug 26 on the breech ring and at the end opposite the above mentioned key slots 13 with an operating arm 24 provided on its lower extremity with a cam-engaging lug 25.

The block is inserted into the breech ring from the bottom with the block-engaging lugs 20 with in the T slot 14 of the breech block and the shaft 7 is inserted through its bearings in engagement with the cylindrical portion 18 of the operating crank. It will be seen that the crank is free to rotate in the breech ring within the limits imposed by the stops 17 and 23 and that this rotary motion is translated by engagement of the lugs 20 with the T-shaped slot 14 into vertical reciprocating motion of the breech block. The handle 21 has been provided in order that the block may be manually operated if desired. It will be noted that the handle is located under the breech block where it may be readily reached when it is desired to operate the block manually. At the same time the handle is out of the way and will not interfere with service of the piece in normal semi-automatic fire from a mount in restricted quarters as in a tank. Guns having handles protruding from the sides of the breech ring cannot be conveniently used in tanks because of the handle interference.

A spring housing 27 has been provided on the left side of the breech ring for the reception of a counterbalancing and closing spring 28. A longitudinal bore 29 in the breech ring serves as a guide for the crosshead 30 on the end of the rod 31. A reduced portion on the front end of the crosshead member provides a seat for a spring bushing 32. The spring 28 is confined on the rod between the bushing 32 and a spring follower 33, retained on the end of the rod by a keyed nut

34. The slotted end of the crosshead is provided with a drag link 35. It will be noted that the spring, rod, and drag link can be assembled as an independent unit and as such inserted in the spring case from the front. A hole 36 in the crosshead and a cooperating hole, not shown, in the guide member 29 are provided in order that a pin may be inserted to temporarily retain the crosshead with the spring in slightly compressed relation. The end of the drag link 35 is provided with a hole 38 to cooperate with a hole 37 through the lever 8 for reception of a retaining pin 39 (Fig. 10). A keyway 40 is formed in hole 37 and a similar keyway 41 is formed in hole 38 (see Fig. 11) to allow the passage of a key 42 formed on the central drag link-engaging portion of the pin 39 (see Fig. 11). Only in the position in which the crosshead is temporarily retained by a pin in hole 36 are the two keyways 40 and 41 in alignment in order that the pin may be inserted through hole 37 with the key 42 engaging the keyway 41 in the drag link. In any other position the key 42 being in engagement with the drag link will have been rotated to a position in which it is opposed by the inner surface of the lever as in Fig. 11. It will be noted that as the lever is rotated in clockwise direction the amount of angular travel required for a given amount of reciprocation of the crosshead will be progressively increased. Similarly the resistance of the spring will increase as it is compressed by the reciprocation of the rod. As the mechanical advantage is thus increasing in practically the same ratio as the spring tension is increasing a substantially uniform force will be applied tending to raise the breech block to closed position.

An extractor mechanism such as that shown in my copending application, Serial No. 393,763, may be provided to extract the fired cases and to retain the breech block in open position until released by the insertion of a fresh round of ammunition.

A bracket 43 is attached to a fixed part of the gun carriage, for example, the cradle (Figs. 1 and 4) and provided with a longitudinal track 44 cooperating with a guide rail 45 attached to the breech ring. The track 44 and guide rail 45 may be formed in any desired manner which will allow the rail to slide longitudinally of the track in the bracket and at the same time will support the bracket against vertical and lateral displacement. The bracket is provided with an upper cam surface 46 attached to the face of the bracket by bolts or the like and with a lower cam plate 47. The bracket is provided with external stiffening ribs 48 and with cam supporting flanges 49 and 50 against which the lower cam 47 is releasably mounted, Figs. 1, 4 and 9. The bracket has been provided on its outer surface with a boss 51 in which parallel intersecting bores 52 and 53 have been formed (Figs. 4 and 9). A screw 54 having an enlarged shank 55 and head 56 is secured to the cam plate 47 (Fig. 9). The diameter of the shank is such that it engages with the smaller diameter bore 52 when the cam plate is in engagement with the supporting flanges. The diameter of the bore 53 is such that when the cam is moved forwardly the head 56 will pass freely through the bore. A plunger 57 and spring 58 are secured in the cam plate 47 by a bushing 59 (Figs. 1 and 4). When the cam plate is in position against the supporting flanges, the plunger 57 engages a hole 60 in the supporting flange 50 to retain the cam plate against forward motion, the plate being secured against lateral

5 movement by the engagement of the head 56 with the surface of the boss 51. The cam plate may be released and removed for replacement or repair by depressing the plunger 57 with a suitable instrument and sliding the plate forward on the bracket as shown in Figure 9.

It will be observed that when the bracket is mounted, the cam-engaging lug 25 on the operating arm 24 will be in position to engage the track formed between the cam plates. As the gun recoils on its mount during firing the lug 25 will be lifted between the cam plates and will serve to rotate the block-operating crank in clockwise direction (Fig. 1) to open the breech. As explained before the block will be retained in open position by the extractor mechanism and as the gun returns to battery the lug 25 will be carried forward above the upper cam plate 46 which terminates short of the forward position of the lug. While the upper cam plate is not directly concerned in the operation of the mechanism it does fill a very important function in that it prevents any bouncing or erratic action due to the resiliency of the operating arm and the lug 25 which on being transmitted to the extractor mechanism might result in faulty ejection. When a new round is inserted, its engagement with the extractor fingers will release the breech block which will close at once under the force of the spring upon the crankshaft arm.

Obviously the operation of the breech mechanism at high recoil velocities imposes a severe strain on the stationary bracket. The provision of the track and guide rail transfers this force to the breech ring thus avoiding any tendency to fracture the bracket near the point of its attachment to the cradle and enabling the use of lighter material in the bracket with improved rigidity and positiveness of operation.

40 It will be noted that the operating arm is well forward on the breech ring and that its cooperating cam surfaces extend only slightly behind the breech ring in battery position. The operating mechanism is thus compact and does not interfere with the movements of the gunners in service of the piece. Further the dragging action of the operating arm causes the operation of the mechanism to be smoother. The operating mechanism does not involve any screws, nuts, bolts, or cotter pins as fastening means in parts which may need to be disassembled in normal operation of the gun. The only tool needed to disassemble the mechanism is a nail or drift pin and disassembly has been effected only with the aid of a match stick.

55 I claim:

1. In a gun, a breech ring and a vertically slideable breech block therein, a breech operating mechanism comprising a shaft journaled in the breech ring, a crank member on and constrained to rotate with said shaft and having an arm engaging the breech block for operation thereof, a lever on an end of the shaft having a key slotted bore, a drag link having a similar key slotted bore in one end thereof, a drag link retaining pin having a key on the drag link engaging portion of its shank complementary to the key slot in the drag link and insertable through the key slot in the lever only in the position in which the key slots in lever and drag link are in register, and spring means engaging the other end of the drag link whereby the breech block will be constrained to closed position, in which position said key slots do not register.

2. An operating cam for an automatic breech

mechanism comprising a bracket plate adapted to be secured at its forward end to a gun cradle, a forwardly facing abutment at the rear end of the inner face of said plate, an upwardly facing abutment at the bottom side of the inner face of said plate, a recessed replaceable cam plate engaging said abutments, and a spring-backed plunger in said recess having a portion engaging said upwardly facing abutment to maintain the cam plate in engagement with said abutments.

3. In a breech closing mechanism, a breech ring reciprocable in recoil and counterrecoil, a breech block vertically movable in the ring, a longitudinally extending bracket adapted for attachment to a gun cradle and provided with a longitudinal track, a guide rail on the breech ring entering said track, said bracket having a cam plate secured thereto having an upwardly facing cam surface, an operating shaft rockably mounted in the ring and extending transversely thereof and provided with an operating lever outside of said ring, a sleeve mounted on said shaft for movement therewith, the sleeve being provided with an arm having continuous operative engagement with the breech block to reciprocate said block, an arm in engagement with said cam surface to open the breech block upon recoil of the ring, a stop arm constructed and arranged to engage a portion of the ring to limit the opening movement of the breech block and an arm extending rearwardly beneath the breech ring for manually rocking the operating shaft to open or close the breech block, means carried by the bracket and cooperating with the cam engaging arm on said sleeve to positively hold the breech block open during counterrecoil of the breech ring, a spring carried by the breech ring for automatically returning the breech block to closed position after a round is chambered, and a pivoted link connecting said spring and said operating lever, whereby the spring is energized upon the recoil of the breech ring.

4. In a breech closing mechanism, a breech ring reciprocable in recoil and counterrecoil and provided with a longitudinal guide rail, a breech block vertically movable in the ring, a bracket provided with a longitudinal track receiving said guide rail to guide said ring in its reciprocating movements, said bracket being adapted for attachment to a gun cradle and having upper and lower cam plates secured thereto, the lower plate having an upwardly facing cam surface terminating at its outer end in a straight surface substantially parallel to said track, the upper plate having a downwardly extending cam surface facing the cam surface of the lower plate and forming between them a cam track, the upper cam plate having an upper straight surface substan-

tially parallel to said track, an operating shaft rockably mounted in the ring and extending transversely thereof and comprising an operating lever, a spring carried by the breech ring and having operative connection with the lever whereby the spring is tensioned during recoil of the breech ring, an arm on the operating shaft having continuous operative engagement with the breech block to reciprocate the same, and another arm on the operating shaft having a portion constructed and arranged to enter said track and engage the said cam track during recoil of the ring to open the breech block and to thereafter engage the straight upper surface of the lower cam plate to positively hold said breech block open on its way to battery during the counterrecoil movement of the ring.

5. In a breech closing mechanism, a breech ring reciprocable in recoil and counterrecoil, a breech block vertically movable in said ring, a longitudinally extending bracket adapted for attachment to a gun cradle, means mounting the breech ring on the bracket for longitudinal sliding movement thereon, an upper and a lower cam plate on the bracket, the lower plate provided with an upwardly facing cam surface and a straight upwardly extending surface at its rear end parallel with the axis of the breech ring, the upper cam plate being provided with a downwardly facing cam surface which, with the cam surface of the lower plate, forms a track between said plates, the upper plate being provided with an upwardly facing surface also substantially parallel with the axis of the breech ring, an operating shaft rockably mounted in the breech ring and extending transversely thereof and provided with an operating lever, said shaft having a plurality of arms mounted thereon for rotation therewith, one of said arms having continuous operative engagement with the breech block to reciprocate the block, and another of said arms constructed and arranged to engage the cam surface of the lower cam plate during recoil of the ring to open the breech block, and to thereafter engage the straight surface of the lower cam plate to positively hold the breech block open on its way to battery during counterrecoil movement of the ring, a stop arm on the operating shaft for engagement with the breech ring to limit the opening movement of the breech block, a spring carried by the breech ring for automatically returning the breech block to closed position after a round of ammunition is chambered in the ring, and a link means pivotally connecting said spring to the operating lever whereby the spring is energized upon recoil of the breech ring.

WILLIAM SUMMERBELL.
